WORLD TIME CLOCK

Joseph C. Owinski, Glen Lake, Minn.

Application November 25, 1949, Serial No. 6,249

Term of patent 14 years

(Cl. D42—7)

To all whom it may concern:

Be it known that I, Joseph C. Owinski, a citizen of the United States, residing at Glen Lake, Hennepin County, Minnesota, have invented a new, original, and ornamental Design for World Time Clock, of which the following is a specification, reference being had to the accompanying drawing, forming a part hereof.

Fig. 1 is a front elevational view of a world time clock, showing my new design; and

Fig. 2 is a top plan view of the same.

I claim:

The ornamental design for a world time clock, substantially as shown.

JOSEPH C. OWINSKI.
